INTERCONNECTION BLOCK

Benjamin J. Lamont, 5642 S. La Brea Ave.,
Los Angeles, Calif.

Filed Sept. 5, 1961, Ser. No. 66,600

Term of patent 14 years

(Cl. D26—1)

FIG. 1

FIG. 2

FIG. 3

FIG. 4

FIGURE 1 is a top plan view of an interconnection block showing my new design;

FIGURE 2 is a side elevational view of the article;

FIGURE 3 is an end elevational view of the article; and

FIGURE 4 is a perspective view thereof.

Opposite side and end views of the article are the same as shown in FIGURES 2 and 3 respectively.

I claim:

The ornamental design for an interconnection block, as shown and described.
